UNITED STATES PATENT OFFICE

WILLIAM H. JONES AND ALBERT H. NELLER, OF FAIRFIELD, IOWA.

HOLDER FOR PAINT BUCKETS AND BRUSHES.

Application filed December 15, 1922. Serial No. 607,063.

To all whom it may concern:

Be it known that we, WILLIAM H. JONES and ALBERT H. NELLER, citizens of the United States, residing at Fairfield, in the county of Jefferson and State of Iowa, have invented a new and useful Improvement in Holders for Paint Buckets and Brushes, of which the following is a specification.

Our invention relates to an improvement whereby the device ordinarily used to hold a paint bucket on the rung of a ladder, or on similar supporting means, may also be used to hold the brush away from the bucket when the painter is making a change in his position, or for any reason, is temporarily not using the brush; and it consists of a clamping attachment secured to the bucket holder and arranged in such a manner that it may be readily adjusted wider apart or closer together to hold brushes of different sizes. Also of other features which will be hereafter described and more specifically set forth in the claims.

In the accompanying drawings forming a part of this specification, Fig. 1 is a perspective of a holder embodying our invention. Fig. 2 is a transverse section on line 2—2 of Fig. 1. Fig. 3 is a side view of a central portion of the bucket holding device. Fig. 4 is a perspective showing one of the brush clamping members detached from the bucket holding device. Fig. 5 a transverse section on line 3—3 of Fig. 1.

Referring to the drawings A represents the bucket-holding device which is preferably an ordinary wire doubled on itself and its central and upper portion being provided with a hook large enough to catch over a ladder rung B. Smaller hooks C are formed on the lower ends of the wire to engage and sustain a bucket bail D. The hooks C are preferably set in opposite directions, as shown in Fig. 1, and standing a distance apart the bail of the bucket may be passed up between them and above the points of the hooks, when being turned a quarter way around and lowered into the hooks C, it will occupy the position shown in Fig. 1. This arrangement will serve to prevent the bail from being accidentally disconnected from the hooks C.

Horizontally disposed brush holding clamps E are secured to a central portion of the bucket holding member, whereby a

brush F may be readily inserted between them, and be securely held thereby, away from the bucket and the paint therein, as also shown in Fig. 1. These clamps may be secured to the holder in different ways without departing from the fundamental spirit of our invention, but the preferable way of attaching them is as follows. The wires forming the bucket holder are bent as shown in Fig. 3, the offset portion G being at some distance from the portions H of the wire. There should be a bent part G in, or on each adjacent portion of the wire, and the bent portions should preferably stand parallel with each other.

The clamping members E are preferably made of elastic sheet metal, with their attaching ends divided into three parts—a central part I, and side portions J. The central portion I should be as much longer than the side portions J as the bent portion G of the wire is distant from the straight portions H. The attaching ends of the clamping members being applied to the bent portions of the bucket holding wire the side portions J will be in contact with the straight portions H of the wire and the central portion I in contact with the offset portion G. The contacting portions of the clamping members then being bent around the portions of the wire with which they are in contact so as to encircle it, the clamping members will be held in rigid contact with the wire and will be prevented from rotating thereon.

The ends of the holder wire being doubled on each other will naturally be disposed to spread apart and will permit the clamping members E to also spread apart. To hold them in their proper position and also to adjust them wider apart or closer together we use a slip loop K. This loop encircles both portions of the wire as shown in Fig. 5, and as it is slipped up toward the ladder rung B it will permit the ends of the wire with the clamps E to spread apart to admit a large brush between the clamps, and as it is slipped down toward the clamps E it will draw them together to hold a smaller brush between them.

As will be seen, it holds the brush in a perpendicular position with the handle upward and the brush close to the bail D, and therefore above the bucket which is not

shown in the drawing, whereby any drippings from the brush will drop into the bucket.

Instead of a single wire doubled together, 5 two wires joined together at their upper ends may be used. In either case the ends of the wire at the lower end should have a tendency to spread apart to a small extent and to be drawn together by slipping the 10 loop K downward on the wire.

The device is exceedingly simple and inexpensive, is easily manipulated, will not be in the way, and is effective in operation.

What we claim is:

15 1. A holder for paint buckets and paint brushes, comprising a vertically disposed member consisting of a wire doubled on itself, at its upper end said upper end having a hook to catch on an overhead support 20 and its lower end having hooks to engage the bail of a paint bucket and thereby support the bucket in combination with, and a pair of oppositely disposed clamping members each member being applied to an adjacent intermediate side of the wire, and being adapted to hold a handle of a paint brush between them above the bail of the 25 bucket.

2. A holder for a paint bucket and paint 30 brushes, comprising a vertically disposed member consisting of a wire doubled on itself at its upper end said upper end being adapted to catch on an overhead support

and its lower end being adapted to engage the bail of a paint bucket and thereby support the bucket, and the adjacent intermediate sides of the wire being offset and said offset portions being parallel with each other, a pair of outstanding horizontally disposed clamping members, each having 40 side portions encircling its adjacent wire above and below the offset in the wire, and an extended central portion encircling the offset portion of the wire substantially, as shown and described. 45

3. A holder for paint buckets and paint brushes, comprising a vertically disposed member consisting of a wire doubled on itself at its upper end, said upper end being adapted to catch on an overhead support 50 and the ends of the wire being disposed to spread apart and adapted to engage the bail of a paint bucket, and a loop member adapted to be slid up and down on the wire, thereby permitting the ends to spread apart 55 or to be drawn together in combination with a pair of oppositely disposed clamping members, each member being applied to an adjacent intermediate side of the wire and adapted to hold the handle of a paint brush 60 between them and above the bail of the bucket.

Fairfield, Iowa, December 6, 1922.
